CLAIM

The ornamental design for a paper dispenser, as shown and described.

DESCRIPTION

FIG. 1 is a bottom, front, and right side perspective view of a paper dispenser showing my new design;

FIG. 2 is a top, front and left side perspective view thereof;

FIG. 3 is a top, front and right side perspective view thereof, with the casing being shown pivoted to an open position;

FIG. 4 is a top, front, and left side perspective view of the wall-mounting plate portion thereof, with the casing omitted for clarity of illustration;

FIG. 5 is a top, rear, and right side perspective view of the wall-mounting portion thereof, with the casing omitted for clarity of illustration; and,

FIG. 6 is a bottom, front, and left side perspective view of the casing portion thereof, with the wall-mounting portion omitted for clarity of illustration.

FIG. 1

FIG. 2

FIG. 3

FIG. 4

FIG. 5

FIG. 6
